Primary Examiner — Susan Bennett Hattan*Assistant Examiner* — Leanne Was(74) *Attorney, Agent, or Firm* — Neal, Gerber & Eisenberg LLP**(57) CLAIM**

The ornamental design for an internal filter for water bottle, as shown and described in the accompanying drawings.

DESCRIPTION

FIG. 1 is a front view of an internal filter for water bottle, in accordance with the present invention. The claimed aspects of the internal filter for water bottle are identical or mirror images of FIG. 1 in a rear view and from left and right sides.

FIG. 2 is a top perspective view of the internal filter for water bottle depicted in FIG. 1; and,

FIG. 3 is a bottom perspective view of the internal filter for water bottle depicted in FIG. 1.

The broken lines in the drawings are provided for environment and depict unclaimed portions of the internal filter for water bottle. They form no part of the claimed design.
